CLOCK

Leo I. Bruce, Framingham Center, Mass., assignor
to General Electric Company, a corporation of
New York

Application May 13, 1954, Serial No. 30,479

Term of patent 14 years

(Cl. D42—7)

To all whom it may concern:

Be it known that I, Leo I. Bruce, a citizen of the United States, residing at Framingham Center, county of Middlesex, Commonwealth of Massachusetts, have invented a new, original, and ornamental Design for a Clock, of which the following is a specification, reference being had to the accompanying drawing, forming a part thereof.

In the drawing the single figure is a front per-

spective view of a clock, illustrating my new design.

The back of the illustrated clock embodying my invention is substantially plain having the usual adjusting knobs extending therefrom.

I claim:

The ornamental design for a clock, as shown and described.
